[57] **CLAIM**

The ornamental design for police-equipment holder with bottom-fastening belt loop, as shown and described.

DESCRIPTION

FIG. 1 is a front elevation of the holder;

FIG. 2 is a side elevational view, the opposite side being a mirror image thereof;

FIG. 3 is a rear elevation of the holder; and,

FIGS. 4 and 5 are top and bottom views respectively of the holder.

The broken line showing of a tear gas canister in FIG. 2 is for illustrative purposes only and forms no part of the claimed design.
